UNITED STATES PATENT OFFICE

CLAUDE C. BUTLER, OF ALIKCHI, OKLAHOMA

AUTOMATIC FIRE EXTINGUISHER

Application filed July 13, 1928. Serial No. 292,463.

This invention relates to an automatic fire extinguishing system embodying weight controlled means for operating valves to admit water to the spray pipes of the system.

5 An important object of the invention is to provide fusible cords for normally holding the weights in their inactive positions, the fusible cords allowing the weights to drop to operate the valves when the cords have 10 been burned by the fire in the building in which the extinguisher is installed.

With the foregoing and other objects in view which will appear as the description 15 proceeds, the invention resides in the combination and arrangement of parts and in the details of construction hereinafter described and claimed, it being understood that changes in the precise embodiment of the invention herein disclosed, may be made within 20 the scope of what is claimed, without departing from the spirit of the invention.

Referring to the drawings:

Figure 1 is a vertical sectional view 25 through a building showing a fire extinguishing system constructed in accordance with the invention.

Figure 2 is an enlarged sectional view illustrating the valve controlling mechanism as in its set position.

30 Figure 3 is an enlarged sectional view through the valve controlling mechanism showing the same as moved to operate the valve.

Referring to the drawing in detail, the fire 35 extinguishing system forming the subject matter of the present invention is shown as installed in a building, the building being indicated generally by the reference character 5, and while I have shown the system installed in a building embodying a single room, it is to be understood that the system may be installed in any number of rooms desired.

An automatic fire extinguishing system 45 constructed in accordance with the present invention embodies spray pipes 6 which are arranged within the building at a point adjacent to the ceiling thereof, pipes 7 arranged between the walls of the building, pipe 8 arranged above the ceiling beams of the build-

ing directly under the roof beams, and pipes 9 disposed exteriorly of the building and arranged in spaced relation with each other across the roof of the building.

The pipes 6, 7 and 8 are supplied with 55 water passing through pipe 10, while the pipes 9 are supplied with water passing through pipe 11, the pipes 10 and 11 being however in communication with the main water supply so that water under pressure 60 will be fed to the spray pipes.

In each of the pipes 10 and 11 is a controlling valve normally held in its closed position to prevent the passage of water through the pipes to the spray pipes. An operating lever 12 is connected with each valve and is adapted to be engaged by means of the sliding weight 13 associated therewith, the sliding weight 13 being normally held in its uppermost position, by means of the pivoted arm 14 which in turn is held in its uppermost position by means of the weight 15 that is supported by the fusible cord 16.

The fusible cord 16 passes through eyes 17 that are located in such relation with respect to each other that the fusible cord may be arranged in proximity to the spray pipes that spray the inner surfaces of the building, while the fusible cord indicated at 18 passes through guides or eyelets 19 arranged exteriorly of the building to normally support the weight 15 associated therewith, and which acts to control the valve in the pipe through which water passes to the spray pipes 9.

Thus it will be seen that due to this construction, should a fire occur exteriorly of the building the fusible cord 18 would be burned, allowing the weight 15 associated therewith, to fall whereupon the weight 13 would overbalance the arm and move to a position to operate the valve lever and open the valve that allows water to pass through the pipe 11 to the spray pipes 9.

Should an interior fire occur, it is obvious that the fusible cord 16 would burn allowing the weight controlled valve operating mechanism to move to open the pipe line 10 and allow water to pass to the spray pipes 6, 7 and 8.

Disposed adjacent to each lever 12, is a blade switch 20 that normally lies in the path of travel of the lever 12 associated therewith, so that when the lever 12 is moved to open the valve, or to a position as shown by Figure 5 of the drawings, a circuit will be completed through the wires 21 and 22 leading to the signal 23 to the end that a signal will be made simultaneously with the opening of the valves to admit water to the spray pipes.

The reference character 24 designates a union whereby air or water under pressure may be directed to the spray pipes to force any foreign matter from the pipes, which would otherwise tend to clog them.

Positioned under the weight 15 is a vertically movable rod 25 pivotally connected with one arm of the bell crank 26 which in turn is mounted in the bracket 27. Rods 28 connect with the bell crank lever at 29 and are designed to have connection with a suitable door operating mechanism for moving the doors to their open positions when the bell crank lever is operated, said operation occurring when the weight 15 falls and engages the upper end of the rod 25.

When the rods 28 are operated, it will be obvious that doors to which they are connected will be moved to their open positions, releasing animals from the building; it being understood that this construction of operating mechanism is especially designed for barns or other out buildings in which stock is housed.

I claim:

A fire extinguishing system including spray pipes, a supply pipe for delivering water to the spray pipes, a valve in the supply pipe, a lever for operating the valve, a vertically movable weight operating on the supply pipe and adapted to move downwardly to contact with the lever to open the valve and admit water to the spray pipes, a weight for normally over-balancing the first mentioned weight, and a fusible cord for normally holding the second mentioned weight in its inactive position.

In testimony that I claim the foregoing as my own, I have hereto affixed my signature.

CLAUDE C. BUTLER
